(57) **CLAIM**

The ornamental design for a midsole periphery as shown and described.

DESCRIPTION

FIG. 1 is a perspective view of the midsole periphery in accordance with my new design;
FIG. 2 is a right side view thereof;
FIG. 3 is a left side view thereof;
FIG. 4 is a front view thereof;
FIG. 5 is a rear view thereof;
FIG. 6 is a top view thereof; and,
FIG. 7 is a bottom view thereof.

The dash-dash broken line showing of the shoe upper and sole is included for the purpose of illustrating environment that forms no part of the claimed design. The dash dot dash lines immediately adjacent the solid-line portions of the shoe define the bounds of the claimed design form no part thereof.

1 Claim, 7 Drawing Sheets
